UNITED STATES PATENT OFFICE.

WILLIAM G. AVERY, OF PAINESVILLE, OHIO.

TOTE-BOX.

1,107,014.

Specification of Letters Patent. Patented Aug. 11, 1914.

Application filed March 9, 1912. Serial No. 682,699.

To all whom it may concern:

Be it known that I, WILLIAM G. AVERY, a citizen of the United States, residing at Painesville, in the county of Lake and State of Ohio, have invented certain new and useful Improvements in Tote-Boxes; and I do hereby declare the following to be a full, clear, and exact description of the invention, such as will enable others skilled in the art to which it pertains to make and use the same.

This invention has reference to metallic boxes more especially designed to be used as what is known as tote boxes such as are employed in factories for the purpose of receiving and moving from place to place manufactured articles such as castings, nails, bolts and nuts and similar small articles.

The objects of this invention are to first provide a box of the type set forth formed of one piece or blank of metal which is turned upon itself to form such box, second to so construct or form the box that it is retained in shape without the necessity of riveting the meeting or overlapping ends or parts; thirdly to so form the box that the corners at which the meeting ends are assembled that the said corners are strengthened due to the multiplicity of the layers of the metal whereby as these layers are congregated and secured after being overlapped the said corners are rigid and the box is made firm and strong where strength and firmness is desired and required; fourthly to so form the corners of the box by a multiplicity of layers or folds at the corners of the box that these corners will provide sufficient stock or material to facilitate electric welding where such a means of uniting the corners is desired; other objects being apparent from the drawings and specification.

This invention consists in the manner of overlapping the metal of the blank at the corners of the box so as to provide the multiplicity of layers as will be hereinafter fully set forth and claimed.

In the drawings, Figure I, is a plan view of a blank which is shaped and cut so as to form a box embodied by this invention. Fig. II, is an isometric view of a box which results from the proper bending and overlapping of the parts of such a blank as is illustrated in Fig. I. Fig. III, is a vertical sectional view taken through line A on Fig. II, and Fig. IV, is a sectional view taken

through line B, on Fig. II, and Fig. V, is a vertical sectional view taken through line C, on Fig. II. Fig. VI is a fragmental view of a blank showing one corner and illustrating the lines of folding for forming a corner such as are embodied in this invention and also illustrating the manner of cutting the same for the purpose of forming the corner. Fig. VII, is a modified form of folding and cutting a corner as are also Figs. VIII and IX. All of the above figures illustrating a few of the manners of cutting and folding the corners of a blank so as to form the corners of a box with a number of layers hereinabove set forth. Fig. X, illustrates the fold of the part D, in Fig. VI. Fig. XI, illustrates the fold of the part E, in Fig. VI. Fig. XII, illustrates the fold of the part F, in Fig. VIII and Fig. XIII, illustrates the fold of the part G, in Fig. VIII. Fig. XIV, represents the folds of the part H in Fig. VII, and Fig. XV represents the folds of the part J in Fig. VII. Fig. XVI and Fig. XVII represent the foldings of the respective parts K and L of Fig. IX.

It will be noticed from the blanks shown in Figs. I, VI, VII, VIII and IX, that the corners are reinforced by numerous folds and that in the greater number of blanks very little metal is removed; overlapping strips being left on the end pieces and side pieces; and that while in such cases where any overlapping part is removed the contiguous part is reinforced by being bent upon itself in such a manner as to provide numerous layers in the corner as is illustrated in Figs. III, IV, X, XI, XII, XIII, XIV, XV, XVI, and XVII; and that these folds are held firm by turning down the upper edge of the continuous walls of the box thus holding the entire structure together, strengthening the corners and providing plenty of stock in case it is desired to weld the corners by means of electricity.

In forming the box as illustrated in Fig. II, the blank as in Fig. I, is bent by folding the edge 1, upon the part 2, forming a double fold; the part 1, being bent upward when the box is formed, (see Fig. III) the cuts 3 of the metal leave tongue like portions 4 which are bent around the corners of the contiguous walls and are then embraced by the hems 5 of said walls which are turned down upon them. The cuts 3 also provide tongues 6 which are turned upon

themselves inwardly, outwardly and around the contiguous wall, this portion being embraced by the double folded hem 1, 2, (see Fig. III). The bent portion of 5 the tongue 6 projects along inwardly at the corner on the outside or inside of the box (preferably outside). By the above it will be seen that the several layers of metal are congregated at the corners of the box by 10 folding the metal upon itself thus supplying means both for strength and for the purpose of welding if desired.

In Figs. VI, VII, VIII, IX, X, XI, XII, XIII, XIV, XV, XVI, and XVII, 15 I have illustrated modified forms of flaps and bendings which will be clearly understood and all of which provide for a multiplicity of folds and layers at the corners in these figures. However, the hem folds 7, 20 are shown as single folds or in other words the metal being bent but once upon itself and the flaps embraced by this hem at the corners bent upon itself and so as to provide a number of layers of suitable thickness 25 at the corners; it being immaterial as to the manner of folding these flaps.

Referring particularly to Fig. VII the manner of folding the metal is as follows: Approximately $\frac{2}{3}$ of the tongue J is bent 30 backward so that approximately $\frac{1}{3}$ rests against the side wall of the box, the hem 7 is then turned down upon the side and tongue, the tongue is then bent so as to overlap the end of the box and then the end hem 35 is turned down upon the cleft so as to hold the box in the folded position. The hem on the side and cleft may be turned more than once if it is desired to form a stronger corner but under ordinary conditions one hem is

all that will be required. From the above 40 it will be seen that four thicknesses of metal is provided at the corner of the box thus preventing the breaking down at this point.

Having thus described my invention, what I claim as new and desire to get protection 45 on is as follows:

1. A tote box of the class described composed of a single sheet of metal having clefts at the corners thereof, tongues formed by said clefts, the metal being bent upward to form 50 the walls of the box, said tongues bent backward against the wall to which the tongue is attached so that approximately one third of said tongue rests against the wall, the remaining portion of said tongue being again 55 bent so as to overlap the contiguous wall of said box, all substantially as and for the purpose set forth.

2. A tote box of the class described composed of a single sheet of metal being provided with tongues at each corner thereof, the metal being bent upward to form the 60 walls of the box, the tongues being bent backward against themselves and overlapping the one wall of the box, a hem 65 turned down on the upper edge of said wall of the box and tongue thus bent, the tongues being again bent to overlap the contiguous wall of the box and means for holding said tongue in the folded position.

Signed at Cleveland, in the county of Cuyahoga and State of Ohio, this 15th day 70 of February, 1912.

WILLIAM G. AVERY.
